COMBINATION PACKAGE

Sidney Recht, Bronx, N. Y.

Application June 20, 1950, Serial No. 169,153

2 Claims. (Cl. 206—47)

1

My invention relates to packaging and more particularly to the packaging of bottles or the like ultimately equipped with droppers for dispensing the contents thereof.

One of the objects of my invention is to provide a container or carton constructed in a manner to permit closing of the carton when the dropper is retained in the bottle and in a manner wherein the bulb of the dropper projects outwardly through the closed top of the carton.

Another object of my invention is to provide a carton of the foregoing described character wherein certain of the closure tabs of the carton function to insure a preestablished positioning of the bottle within the carton and thus permit the bulb to extend through an opening formed in the cover tab.

A further object of my invention is to provide a carton of the foregoing described character wherein the cover tab surrounds the bulb in a manner to preclude deterioration of the contents of the bottle, for example, by light rays from without the carton.

Another object of my invention is to provide a carton of the foregoing described character which is simple in construction, durable in use, efficient in operation and economical in manufacture.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a perspective view of a carton constructed in accordance with my invention.

Figure 2 is a view similar to Figure 1 but illustrating the carton in partially opened position.

Figure 3 is a vertical sectional view of the carton illustrating the arrangement of the bottle and dropper therein as packaged for distribution.

Figure 4 is a view similar to Figure 3 but illustrating the dropper as applied to the bottle.

In practicing my invention, as illustrated in the drawing, I provide a carton 5 constructed of cardboard or the like and having initially packaged therein a bottle 6 containing liquid, for instance, a medicinal preparation, and which bottle is provided with a replaceable stopper or closure cap 7 threaded about its neck. Disposed within the carton, adjacent the bottle, is a tubular mem-

2

ber 8 of cardboard or the like and which member has its upper end extending within an inferiorly threaded closure or dropper-cap 9. The top of the cap 9 has fixed thereto and extending therethrough a glass or similar tube 10 of a medicine dropper D and which tube 10 is disposed within the member 8 for protection against breakage, etc., the lower end of the tube being constricted while its upper end is equipped with the usual compressible bulb 11.

The carton 5 is formed with the usual side and end walls 12 and 13, respectively, and a bottom 14. The upper ends of the end walls 13 are provided with closure flaps 15, respectively, while one of the side walls 12, at its upper end, is provided with a top flap 16 foldable over the flaps 15 and terminating in a folding end section 17 insertable between the inner face of the opposite side wall 12 and the adjacent edge faces 18 of the side flaps 15 at the top of the carton. The length of the flaps 15 is such as to provide a space therebetween, when disposed in their closed positions, which is substantially equal to the outside diameter of the bulb 11 whereby to permit projection of the bulb between their confronting edge faces and to thus denote the position of the bottle within the carton as hereinafter more fully described. The flap 16 is perforated as at 19 to provide a centralized discal knock-out section 19 which, when removed, defines an opening 20 in the flap 16 through which the bulb 11 projects.

The carton is distributed with the flaps 15 and 16 in sealed and closed positions and with the bottle 6, tubular member 8 and dropper D arranged as illustrated in Figure 3. In order to use the contents of the bottle, the flaps 15 and 16 are opened in the usual manner and the bottle 6, member 8 and dropper D removed from the carton whereupon the stopper 7 and member 8 are discarded. The dropper D is then used to dispense the contents in the usual manner. After use, the cap 9 is threaded onto the neck of the bottle and the latter inserted within the carton, the flaps 15 being folded to closed position and centralizing the bottle with the bulb extending upwardly between the flaps 15. At this point, or previously, the knock-out section 19 having been removed, the flap 16 is closed over the flaps 15 with the bulb projecting through the opening 20. When the bottle is thus enclosed within the carton, it is protected from breakage and the contents thereof from deterioration by exposure to any light outside of the carton.

From the foregoing, it will be apparent that I have provided a carton wherein means is provided

to permit closing of the carton after the applicator or dropper is utilized as a closure means for the bottle, it being understood that cartons are manufactured in substantially the smallest size for accommodating the bottle and dropper disassembled, whereby to conserve shipping and storage space, it not being desirable to lengthen the carton because of shifting of the bottle within the carton and for economic and other reasons. It is to be noted that the stopper 9 of the dropper engages the shoulder of the bottle and also one of the end walls 13 of the carton, while the bulb 11 engages the underface of one of the flaps 15. The lower end of the member 8 is seated on the bottom 14 while one side of the bottle engages the other wall 13, thus, the elements coact with each other and the carton to preclude shifting of the bottle therein when thus packaged and to form a compact assembly as illustrated in Figure 3 of the drawing.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefor as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In combination, a carton provided with a cover flap closing the top of said carton and being operable for opening said top, a container disposed within said carton adjacent one side thereof and being initially equipped with a stopper for distribution within said carton, a tubular member disposed in said carton interjacent said container and the other side of said carton, an applicator normally disposed within said carton in detached relation with said container, said applicator being provided with a closure cap seated upon one end of said member and a dispensing tube extending from said cap into said member for protection of said tube by said member, a compressible bulb connected to said tube and extending from said cap into engagement with the top of said carton whereby said applicator coacts with said container and said member to form a compact assembly disposed wholly within the confines of said carton, said cap being attachable to said container in lieu of said stopper when said

top is open to permit dispensing of the contents of said container by said applicator, said flap having a rupturable section with the latter being removed and defining an opening, the distance from the top of said container to said flap being less than the length of said bulb whereby said bulb extends out of said carton through said opening when said cap is so attached and said container disposed within said carton with the top closed by said flap.

2. In combination, a carton provided with a cover flap and a pair of oppositely disposed top flaps foldable under said cover flap for closing the top of said carton and with said flaps being operable for opening said top, a container disposed within said carton adjacent one side thereof and being initially equipped with a stopper for distribution within said carton, a tubular member disposed in said carton interjacent said container and the other side of said carton, an applicator normally disposed within said carton in detached relation with said container, said applicator being provided with a closure cap seated upon one end of said member and a dispensing tube extending from said cap into said member for protection of said tube by said member, a compressible bulb connected to said tube and extending from said cap into engagement with one of said flaps whereby said applicator coacts with said container and said member to form a compact assembly disposed wholly within the confines of said carton, said cap being attachable to said container in lieu of said stopper when said top is open to permit dispensing of the contents of said container by said applicator, said cover flap having a rupturable section with the latter being removed and defining an opening, the distance from the top of said container to said cover flap being less than the length of said bulb whereby said bulb extends out of said carton through said opening when said cap is so attached and said container disposed within said carton with the top closed by said cover flap, said top flaps being of a length to dispose their confronting end faces on opposite sides of said bulb and said opening to define a space between said faces substantially corresponding to the width of said opening to thus insure positioning of said container within said carton at a location to facilitate said extension of said bulb through said opening.

SIDNEY RECHT.
